UNITED STATES PATENT OFFICE

ARTHUR F. WORDEN, OF BROOKLYN, NEW YORK, ASSIGNOR TO AMERICAN DISTRICT
TELEGRAPH COMPANY, OF NEW YORK, N. Y., A CORPORATION OF NEW JERSEY

DESIGN FOR A SERVICE-CAP EMBLEM OR SIMILAR ARTICLE

Application filed June 16, 1930. Serial No. 36,079. Term of patent 14 years.

To all whom it may concern:

Be it known that I, ARTHUR F. WORDEN, citizen of the United States, and resident of Brooklyn, in the county of Kings and State of New York, have invented a certain new, original, and ornamental Design for Service-Cap Emblem or Similar Article, of which the following is a specification, reference being had to the accompanying drawing, forming part thereof.

Fig. 1 is a front elevational view of a service cap emblem or similar article showing my new design.

Fig. 2 is a top plan view.

I claim:

The ornamental design for a service cap emblem or similar article, as shown.

Signed at New York, in the county of New York and State of New York this twelfth day of June, A. D. 1930.

ARTHUR F. WORDEN.
